(57) **CLAIM**

The ornamental design for a buttstock angle adapter, as shown and described.

DESCRIPTION

FIG. 1 is an exploded isometric view of a buttstock angle adapter showing my new design, a front half and a rear half of the buttstock angle adapter are positioned between a buttstock (on the left of FIG. 1) and a recoil pad (on the right of FIG. 1);

FIG. 2 is an assembled side elevational view of the Buttstock angle adapter shown in FIG. 1, wherein the front half and the rear half of the buttstock angle adapter are positioned between the buttstock and the recoil pad;

FIG. 3 is a top isometric view of the front half of the buttstock angle adapter shown in FIG. 1;

FIG. 4 is a bottom isometric view of the front half of the buttstock angle adapter shown in FIG. 1;

FIG. 5 is a front side elevational view of the front half of the buttstock angle adapter shown in FIG. 1;

FIG. 6 is a right side elevational view of the front half of the buttstock angle adapter shown in FIG. 1;

FIG. 7 is a rear side elevational view of the front half of the buttstock angle adapter shown in FIG. 1;

FIG. 8 is a left side elevational view of the front half of the buttstock angle adapter shown in FIG. 1;

FIG. 9 is a top plan view of the front half of the buttstock angle adapter shown in FIG. 1;

FIG. 10 is a bottom plan view of the front half of the buttstock angle adapter shown in FIG. 1;

FIG. 11 is a top isometric view of the rear half of the buttstock angle adapter shown in FIG. 1;

FIG. 12 is a bottom isometric view of the rear half of the buttstock angle adapter shown in FIG. 1;

FIG. 13 is a front side elevational view of the rear half of the buttstock angle adapter shown in FIG. 1;

FIG. 14 is a right side elevational view of the rear half of the buttstock angle adapter shown in FIG. 1;

FIG. 15 is a rear side elevational view of the rear half of the buttstock angle adapter shown in FIG. 1;

FIG. 16 is a left side elevational view of the rear half of the buttstock angle adapter shown in FIG. 1;

FIG. 17 is a top plan view of the rear half of the buttstock angle adapter shown in FIG. 1; and,

FIG. 18 is a bottom plan view of the rear half of the buttstock angle adapter shown in FIG. 1.

(Continued)

The broken lines in FIGS. 1-18 are included for the purpose of either illustrating environment or portions of the buttstock angle adapter that form no part of the claimed design.
